CLAIM

I claim the ornamental design for an eyelash storage binder insert, as shown and described.

DESCRIPTION

FIG. 1 is a top right perspective view of an eyelash storage binder insert showing my new design;

FIG. 2 is a front view of the eyelash storage binder insert of FIG. 1;

FIG. 3 is a back view of the eyelash storage binder insert of FIG. 1;

FIG. 4 is a side view of the eyelash storage binder insert of FIG. 1;

FIG. 5 is a top view of the eyelash storage binder insert of FIG. 1; and,

FIG. 6 is a bottom view of the eyelash storage binder insert. The broken lines in the figures represent portions of the article which form no part of the claim.
